UNITED STATES PATENT OFFICE.

CHARLES M. BANKS, OF PHILADELPHIA, PENNSYLVANIA, ASSIGNOR OF ONE-FOURTH TO ST. JOHN W. MINTZER, OF SAME PLACE; ELLA J. BANKS, ADMINISTRATRIX OF SAID CHARLES M. BANKS, DECEASED.

BABY-CARRIAGE.

SPECIFICATION forming part of Letters Patent No. 341,824, dated May 11, 1886.

Application filed November 25, 1884. Serial No. 148,800. (No model.)

To all whom it may concern:

Be it known that I, CHARLES M. BANKS, a citizen of the United States, residing at Philadelphia, in the county of Philadelphia and State of Pennsylvania, have invented certain new and useful Improvements in Baby and other Carriages, of which the following is a specification, reference being had therein to the accompanying drawings, wherein—

10 Figure 1 is a side elevation of the baby-carriage or perambulator in its normal or complete state. Fig. 2 is a front elevation of same. Fig. 3 is a front or end view of carriage folded or knocked down for transportation purposes. 15 Fig. 4 is a side elevation of same, and Fig. 5 is a broken vertical section, showing construction of axle for the wheels of the carriage.

My invention has relation to baby or other like carriages or perambulators of the form 20 adapted to be folded together or knocked down into compact shape for transportation purposes; and it has for its object to so construct and secure together all the component parts of the carriage or vehicle, that its body 25 is susceptible of being folded together, its wheels readily removed from the axles, and adapted to be placed upon the folded carriage-body, to reduce and maintain said parts in a compact or "knocked-down" condition of the 30 least attainable space possible for transportation.

My invention accordingly consists of the combination, construction, and arrangement of parts comprising a baby-carriage or like 35 vehicle capable of being knocked down, as hereinafter described and claimed, having reference particularly, first, to a folding body having elastic supports or straps secured to pivoted sustaining bars or levers; second, to 40 a folding body having hinged corner clasps or strengthening-pieces provided with fastening locks or catches; and, third, to wheels having permanently-attached axles which are adapted to swivel upon the axle-bars.

45 In the drawings, A represents a carriage or vehicle composed of body B, axle-bars C C, reach D, and wheels E E. The body B is made up of a bottom, b, hinged or folding ends b' b'', and sides b³ and b⁴. The lines of hinging of

the sides and ends are in different planes, as 50 shown, to provide for the convenient folding of said parts over one another. Each corner of the body B is provided with hinged clasps or strengthening-pieces b⁵, which have fastening hooks, pins, or catches b⁶, as more plainly 55 shown in Fig. 2, for firmly maintaining the sides and ends of the body in their normal or upright position when unfolded or set up for use. The catches or locks b⁶ may be of any of the well-known forms of spring-catches, or 60 constructed and arranged for operation in any desired or suitable way. The axle-bars C are provided with ears e e, in which are provided bent levers, bars, or standards e', to the outer ends of which are fastened two elastic bands, f 65 f'; or a single band doubled upon itself may be substituted. Bands f pass around and elastically support the carriage-body, while bands f' are fastened at f' to the reach, for maintaining pivoted bars e' and carriage-body in their 70 vertical position. Undue longitudinal and lateral vibration of the carriage-body is prevented by an elastic band, g, which is fastened at g' to the reach D and at its ends g² g² to the bottom of the carriage-body, as more plainly 75 shown in Fig. 1. The wheels E have permanently-attached axles e, which are formed with preferably tapering sockets e', for the reception of correspondingly-shaped ends e² of the axle-bars C, which ends have a groove, e³, into 80 which passes a pin or bolt, e⁴, for swiveling the axles e to the axle-bars C, as shown more plainly in Fig. 5, in order that the former may easily and instantly be placed upon and detached from the carriage-body.

85 The operation of closing or knocking down the vehicle is obvious. The clasps are first unlocked, and the sides and ends of body B, as well as the levers C' are folded, and the wheels E detached and placed upon the folded 90 body B, as shown in Figs. 3 and 4. All the parts of the vehicle are thus reduced to as compact a form as is possible, in order that they may occupy but little space while undergoing transportation.

95 While I have shown and described my invention as being especially applicable to baby-carriages, I do not limit myself thereto, as it

is evident that it may be applied to other vehicles, if desired. So, too, it is obvious that the elastic bands $f f' f^2$ may be used in connection with carriages having non-folding bodies, in which case the levers c' may or may not be pivoted.

Any suitable handle or push-rod, K, may be employed. (See Fig. 1.) I prefer to pass it through eyes k , secured to the body B, so that said rod K may be detached from body B. By employing a duplicate set of eyes, k , at each end of the body, the rod K is susceptible of being reversed, to be used for either a push or pull rod. It is held in place when inserted in eyes k by any suitable form of spring-catch.

What I claim is—

1. The carriage-body B, supported upon transverse elastic bands attached to upright standards or bars, substantially as shown and described.
2. The folding carriage-body B, in combination with pivoted levers or bars c' , and supporting-bands, substantially as shown and described.
3. In combination with a carriage-body, B, the standards c' , bands f and f' , one of which

is fastened at its middle to the reach for said body, substantially as shown and described.

4. A folding carriage-body having hinged corner-clasps and locking-latches, in combination with pivoted standards c' and elastic supports or bands $f f'$, substantially as and for the purpose set forth. 30

5. A carriage composed of a body having folding ends and sides, supporting bands and 35 bars, and detachable wheels, substantially as shown and described.

6. In a carriage, the axle-bars C, having pivoted levers c' , elastic bands $f f'$, body B, and longitudinal elastic band g , substantially as 40 shown and described.

7. In a carriage, the pivoted levers c' and flexible or elastic bands f and f' , the latter being fastened to the reach for the carriage, substantially as shown and described. 45

In testimony whereof I affix my signature in presence of two witnesses.

CHAS. M. BANKS.
